(57) **CLAIM**

The ornamental design for a monkey plush toy, as shown and described.

DESCRIPTION

FIG. 1 is a perspective elevation view of a monkey plush toy showing our new design;

FIG. 2 is a top plan view of the embodiment of FIG. 1;
FIG. 3 is a front elevation view of the embodiment of FIG. 1;
FIG. 4 is a right side elevation view of the embodiment of FIG. 1;

FIG. 5 is a left side elevation view of the embodiment of FIG. 1;

FIG. 6 is a rear elevation view of the embodiment of FIG. 1;
and,

FIG. 7 is a bottom plan view of the embodiment of FIG. 1.
Surface shading is used to shade FIGS. 1-7 to show clearly the character and contour of all surfaces of the 3-dimensional aspects of the design and form a part of the design sought to be protected.
